(57) **CLAIM**

We claim the ornamental design for an LED light panel, as shown and described.

DESCRIPTION

FIG. 1 is a Front Perspective view of an LED light panel showing my new design;

FIG. 2 is a Back Perspective view thereof;

FIG. 3 is a Right-side view thereof;

FIG. 4 is a Left-side view thereof;

FIG. 5 is a Front view thereof;

FIG. 6 is a Back view thereof;

FIG. 7 is a Top view thereof;

FIG. 8 is a Bottom view thereof; and,

FIG. 9 is a Perspective view of an LED light panel showing in zoom position.

The broken lines in the drawings depict portions of the LED light panel that form no part of the claimed design.
